UNITED STATES PATENT OFFICE.

JOHN L. FLANNERY, JR., OF CHICAGO, ILLINOIS, ASSIGNOR TO THE BOYE NEEDLE COMPANY, OF CHICAGO, ILLINOIS, A CORPORATION OF ILLINOIS.

DESIGN FOR A DISPLAY-CABINET.

52,870.

Specification for Design.

Patented Jan. 14, 1919.

Application filed October 3, 1918. Serial No. 256,756. Term of patent 7 years.

To all whom it may concern:

Be it known that I, JOHN L. FLANNERY, Jr., a citizen of the United States, residing at Chicago, county of Cook, and State of Illinois, have invented a new, original, and ornamental Design for a Display-Cabinet, of which the following is a specification, reference being had to the accompanying drawing, forming a part hereof.

The figure is a perspective view of a display cabinet, in accordance with the design.

I claim:

The ornamental design for a display cabinet, as shown.

JOHN L. FLANNERY, JR.
